UNITED STATES PATENT OFFICE.

JOHN P. KANNALEY, OF ALBANY, NEW YORK, ASSIGNOR OF ONE-HALF
TO WILLIAM H. KING, OF SAME PLACE.

HEEL OR TOE PLATE.

SPECIFICATION forming part of Letters Patent No. 311,009, dated January 20, 1885.

Application filed September 6, 1883. (No model.)

To all whom it may concern:

Be it known that I, JOHN P. KANNALEY, of the city and county of Albany, and State of New York, have invented certain new and useful Improvements in Heel and Toe Plates; and I do hereby declare the following to be a full, clear, and exact description of the invention, such as will enable others skilled in the art to which it pertains to make and use the same, reference being had to the accompanying drawings, which form part of this specification.

The nature of my invention consists of corrugated pieces of metal made to conform to the shape of the heel or toe. If the same is to be used for the heel, the ends of the metal pieces are bent on and over the breast of the heel, and fastened thereto by nails or screws driven into the heel from the under side and through holes in the projections on the breast into the breast of the heel. If the same is to be used for the toe, the pieces are bent to the shape of that part of the sole which it is intended to cover, and then fastened to such sole by nails.

By the use of my invention cheapness of manufacture and cost, lightness, and elasticity are secured, the knocking off and rattling of plates are prevented, the possibility and trouble of driving nails or screws into or through the nail-holes of the heel are obviated, and the ease of adding plates to the heel or toe is brought about. By reason of the plates being corrugated, slipping is prevented, and the

plates being made of malleable metal they can 35 be bent to conform to any shape or size of heel or toe.

In the drawings, Figure 1 is a plan view of the heel-plate constructed according to my invention, and as fastened on the heel. Fig. 2 is 40 a plan view without the heel. Fig. 3 is a modified form of the plate as sometimes made by me for larger-sized heels, and especially for toe-plates.

In the drawings like letters refer to like 45 parts.

In the drawings, A represents the plate; B, the projecting ends, which are fastened to the breast of the heel; C, projections on the inside of the plate, through the holes in which nails 50 or screws are driven into the heel or sole; D, the nail or screw holes; E, the heel; F, a groove in which may be punched small holes for the purpose of driving more nails therein.

Having thus described my said invention, 55 what I claim, and desire to secure by Letters Patent, is—

A skeleton sole or heel plate having projections on the inner periphery thereof, through which apertures are made for the insertion 60 of nails or screws in attaching it, and also provided with perforated lugs bent downwardly from the front ends thereof, to secure it to the breast of the heel when used as a heel-plate, as set forth.

Witnesses. JOHN P. KANNALEY.
